US0D1035543S

(12) **United States Design Patent** (10) **Patent No.:** **US D1,035,543 S**
(45) **Date of Patent:** **** Jul. 16, 2024**

(54) **MOTORBOAT**

(71) Applicant: **MOEBIUS TECHNOLOGY (SINGAPORE) PTE.LTD.**, Singapore (SG)

(72) Inventor: **Xiaoning Liang**, Neijiang (CN)

(73) Assignee: **MOEBIUS TECHNOLOGY (SINGAPORE) PTE. LTD.**, Singapore (SG)

(**) Term: **15 Years**

(21) Appl. No.: **29/858,962**

(22) Filed: **Nov. 5, 2022**

(30) **Foreign Application Priority Data**

Oct. 31, 2022 (EM) 015001976-0002

(51) **LOC (14) Cl.** **12-06**
